UNITED STATES PATENT OFFICE.

LUTHER C. CROWELL, OF BROOKLYN, ASSIGNOR TO ROBERT HOE, STEPHEN D. TUCKER, THEODORE H. MEAD, AND CHARLES W. CARPENTER, OF NEW YORK, N. Y.

NEWSPAPER-WRAPPING MACHINE.

SPECIFICATION forming part of Letters Patent No. 508,567, dated November 14, 1893.

Application filed January 22, 1892. Renewed April 21, 1893. Serial No. 471,354. (No model.)

To all whom it may concern:

Be it known that I, LUTHER C. CROWELL, a citizen of the United States, residing at Brooklyn, in the county of Kings and State of New York, have invented certain new and useful Improvements in Newspaper-Wrapping Machines, fully described and represented in the following specification and the accompanying drawings, forming a part of the same.

10 The object of the present invention is to provide an improved machine of that class used in wrapping papers and other publications for mailing and generally known as newspaper wrapping machines, and especially to provide a simple and efficient wrapping machine of high capacity.

In a prior application, I have described and claimed broadly a machine for wrapping newspapers in which the paper and wrapper 20 are wound upon a central core, the pasted wrapper secured about the core, and the wrapped paper removed from the core either by pushing the paper from the core or withdrawing the core from the paper. In the 25 construction shown in that application as one of the preferred forms of such machines, the paper was gripped by a core and the paper and wrapper wound upon the core and the wrapper secured by pressure between the core 30 and a wiper outside the core either by the rotation of the core with the paper and wrapper pressed against a stationary wiper or by rotating a wiper about a stationary core.

In constructions embodying the present 35 invention, the paper and wrapper are not gripped by the core but I employ feeding devices co-acting with the core to wind the paper and wrapper thereon, the paper and wrapper being advanced by pressure between the 40 feeding devices and core. It is evident that the core and feeding devices and the manner in which they co-act to wind the paper and wrapper upon the core and secure the wrapper may be varied, and that the wrapped paper 45 may be delivered from the core in different ways. I prefer, however, to use a rotating core and positively driven belts as the feeding devices co-acting therewith, and I preferably mount the core and belts to move longitudinally of the wrapped paper and deliver

the latter by withdrawing the core and belts therefrom. The core may consist of a single cylinder and the paper be supported through the whole or a part of its width, but I prefer to form the core of two cylinders supporting 55 the paper at its opposite side edges, and deliver the paper by withdrawing the two cylinders and their respective belts in opposite directions, a sufficient support for the paper being thus provided with a small delivery 60 movement, even for wide papers.

In the accompanying drawings I have shown my invention as embodied in a machine of the preferred form, and a full description thereof will now be given, and the features 65 forming my invention specifically pointed out in the claims.

Referring to the drawings: Figure 1 is a side elevation of the machine. Fig. 2 is a sectional side elevation looking in the same 70 direction, the section being taken inside the frame. Fig. 3 is a plan view. Fig. 4 is a front elevation of the machine looking to the left in Figs. 1 and 2. Fig. 5 is a section on line 5 of Fig. 2 showing the parts in the position they occupy in receiving a paper. Fig. 6 is a section on the line 6 of Fig. 4 on an enlarged scale, showing the parts in the position they occupy in receiving a paper. Figs. 7 and 8 are diagrammatic sections similar to 80 Fig. 6 showing the parts in different positions, Fig. 7 showing the paper as partially wrapped and Fig. 8 as completely wrapped and being delivered. Fig. 9 is a view similar to Fig. 7 showing a slightly modified method of wrapping. Figs. 10 and 11 are perspective views of products of the two methods, the scale being that of the general views.

The frame of the machine may be of any suitable form to support the operating parts. 90 As shown, it consists of the opposite end frames A, B, and base frame C on which they are mounted. At the top of the machine the main driving shaft D is mounted in the end frames A, B, this shaft being driven from any 95 suitable source of power.

The paper and wrapper are introduced into the machine at the upper part of the front side, and the core, belts and other parts of the wrapping mechanism are mounted in the 100

lower central part of the machine in two inferior vertical frames E, F, which slide in grooves 10 in the base plate C so as to be moved outward in opposite directions in delivering 5 the paper.

The wrapped papers are shown as received by a flattening and delivering mechanism mounted below the core in the stationary frames A, B, and delivered thereby at the rear 10 side of the machine, this flattening and delivering mechanism consisting in the form shown of series of converging tapes by which the papers are advanced and gradually flattened. The parts forming the wrapping mechanism proper will first be described. 15

The core upon which the paper and wrapper are wound, and about which the wrapper is secured, consists in the preferred form, as shown, of two short cylinders G mounted so 20 as to support the paper at opposite sides and with each of these cylinders co-operate feeding devices which consist in the form shown of belts H of leather or other suitable material co-acting with the surfaces of the cylinder 25 forming the core to advance the paper and wrapper. The belts, as shown in Figs. 4 and 5, are preferably of the same or substantially the same width as the cylinders G, so that the paper is engaged by a large surface, but it 30 will be understood that this is not absolutely essential:

As the construction of the cylinders G, belts H, and actuating devices therefor, is identical at the two ends of the machine, the same reference letters and figures will be used for 35 both, and a description of the left hand end of the machine in Fig. 5 will be understood to apply also to the opposite end.

The cylinder G is mounted to rotate freely 40 upon a stud 11 carried by the sliding frame E, and the belt H is carried by driving pulleys 12, 13, mounted on opposite sides of the cylinder G so as to strain the belt about the cylinder, and by pulley 14 mounted in the 45 rear lower part of the frame. The belt driving pulleys 12, 13 are carried by shafts 15 mounted to rotate in sleeves 16 on frame E. The pulley 14 is carried by an arm 17 pivotally mounted in the frame E by a short shaft 50 18 passing through the frame and provided with a crank arm 19, so that the pulley 14 may be raised and lowered to loosen and tighten the belt, the arm 19 being normally pressed into position to hold the belt taut by 55 spring 20 coiled about a rod 21 pivoted to the arm 19 and sliding in bracket 22 on frame E. The belt H is thus held under spring tension allowing it to yield as the paper is wound upon the cylinder G, and the pulley 14 may 60 be raised by rocking the shaft 18 so as to loosen the belt and allow the cylinder and belt to be readily withdrawn from the wrapped paper. To insure the movement of the belt with the pulleys when withdrawn to deliver 65 the wrapped paper, the construction shown is preferably used, in which the pulleys 12, 13 and 14 are provided with grooves, and the

belt H carries a series of projections 23 on its inner surface which run in and are held by the grooves.

For securing the proper movements of the cylinder G and belt H in wrapping and delivering the paper I provide the following connections with the main shaft D, the parts being so timed that the paper and wrapper 70 are wrapped upon the core, and the wrapper secured about the core during two rotations of the latter, and during the next rotation the core and belts are withdrawn from the ends of the wrapped paper to release it and 75 returned to normal wrapping position to receive another paper. It will be understood, however, that any other suitable form of driving connections may be used, that the paper may be wrapped any desired number of times 80 upon the core, and that more than the time of one rotation may be used in withdrawing and returning the core and belts if desired, the driving connections being readily varied for this purpose. 85

The frame E carries on its upper side a shaft 24 rigid therewith and adapted to slide through a sleeve 25 in the frame A. This shaft 24 carries at its outer end outside the frame A a bracket 26, and in the upper end of this bracket 90 and in the frame E is mounted a shaft 27. The main shaft D carries a gear 28 which meshes with a broad faced gear 29 keyed to the shaft 27 just described, so that the gear 29 remains in mesh with the gear 28 as the frame 95 E is reciprocated, and this broadfaced gear 29 meshes with the gear 30 on belt driving pulley 12. The pulley 12 carries a gear 31 which meshes with a gear 32 on the cylinder G, and the cylinder G drives belt pulley 13 by a gear 100 33 on the roll meshing with gear 32, so that the belt and cylinder G are driven at the same rate of speed. As shown, and as above stated, the gears are so timed that the cylinder G is rotated three times to each rotation 105 of the shaft D.

The shaft 24 carries inside the frame A a sleeve 34 preferably adjustable on the shaft by a set screw as shown, and provided with a stud or bowl 35 which is engaged by a forked 110 lever 36 pivoted on a fixed part of the machine, and provided at its opposite end with a bowl which runs in a cam groove 37 formed in a cam wheel I carried by the shaft D, this cam, as shown, being so formed, that the 115 frame E and parts carried thereby are held in their inner position for wrapping during two revolutions of the core and then withdrawn for delivering the wrapped paper and returned to position for receiving another 120 paper during the third revolution. The shaft 18 is rocked to raise the pulley 14 and loosen the belt H as the parts are withdrawn for delivering the wrapped paper, this being effected by means of a stationary cam 38 carried by the frame A and engaging the arm 19 as the frame is withdrawn. 125

Any suitable form of feeding devices may be used for advancing the paper and wrap-

per to the core and belts. As shown, the paper and wrapper are advanced over a series of guides 39 by a feeding roll 40 and series of feeding disks 41, the latter projecting 5 between the guides. The guides 39 extend partially about the curved path of the paper between the cylinders G and are preferably made of spring metal so as to yield as the head of the paper and wrapper are brought 10 above them on the first revolution and beneath them on the second revolution of the core. The guides are also preferably spring pressed toward the core, being shown as adjustably mounted on a shaft 42 which carries 15 an arm 43 spring pressed by a spring 44 coiled about a rod 45 pivoted to the arm 43 and sliding in a bracket 46 on the frame A, a stop 47 being preferably provided, against which the spring 44 holds the arm 43.

20 The shaft of feeding roll 40 and the shaft of the feeding disks 41 are geared together by gears 48, and 49 and the shaft of roll 40 carries another gear 49, by which it is driven from the shaft D through an intermediate 25 50 meshing with a gear 51 carried by the shaft D, the feeding mechanism being timed, as shown, so that the feeding roll 40 and feeding disks 41 are driven at the same rate of speed as the core G and belts H.

30 With the construction shown, in which the tape rolls 12, 13 are separated a considerable distance on opposite sides of the path of the paper as it passes to the core, space is provided for a guide by which the paper is directed 35 about the core at this part of its movement, and I prefer to use this guide to aid in delivering the paper by moving it between the two end cylinders forming the core as the paper is released thereby, so as to carry the 40 paper out of line of the core and deliver it to the flattening or other delivery mechanism provided for receiving the paper the guide thus forming an ejector moving transversely to the paper.

45 The guide 52 consists in the form shown of a plate bent to conform substantially to the curve of the cylinder G forming the core, and extending substantially the full width of the paper opposite and between the cylinders. 50 This guide 52 is carried by arms 53 adjustably secured upon a rod 54 which is carried in arms 55 on a rock shaft 56 mounted in the frames A B. Outside the frame A this shaft 56 carries a crank arm 57 which is provided 55 with a bowl engaged by a cam 58 on a cam disk K carried by the shaft D, so that the shaft 56 is rocked once in each revolution of the shaft D to throw the guide 52 inward between the two cylinders forming the core, as 60 shown in Fig. 9, the guide 52 being returned to normal position by a spring 59 coiled on a rod 60, sliding in a bracket 61 on the frame A, and pivotally connected to a second crank arm 62 on shaft 56.

65 It is evident that the wrapped paper may be allowed to drop directly from the core when released therefrom without the use of the mov-

able delivering guide or ejector 52, or that the guide 52 may deliver the paper directly to a receptacle. When the paper extends 70 about the core one or more times so as to form a circular product, however, I prefer to provide a flattening mechanism by which the wrapped paper will be reduced to a flat form. Any suitable form of flattening mechanism 75 may be used for this purpose, but I have shown a simple and efficient construction in which a pair of converging delivering tapes are used to which the wrapped paper is delivered from the core. These delivering and 80 flattening tapes L are mounted to run on opposite sides above and below the cylinders G, forming the core, each pair of tapes being carried by driving pulleys 62 and pulleys 63, the pulleys 63 being preferably carried, as shown, 85 by bars 64 adjustable in brackets 65 which are adjustably mounted on shafts 66 carried by the frame of the machine so that the belts may be adjusted to take up slack, and also to vary the position of the receiving ends of 90 the belts relatively to the core. The belt driving pulleys 62 are geared together by gears 67 and are driven from shaft D by gear 68 on the shaft of one of the pulleys, gear 69 on the shaft D, and intermediate 70. 95

The operation of the machine is as follows:— It will be understood that the wrapping and delivering mechanism may form a complete machine and the papers and pasted wrappers be fed thereto by hand, but suitable devices 100 will preferably be combined therewith, by which the paper and wrapper shall be fed to it in proper time and paste be applied to secure the wrapper, an automatic machine of high capacity being thus produced. It will 105 be understood, also, that the wrapping and delivering mechanism may be combined with suitable wrapper feeding and pasting devices, and the delivering mechanism of a printing press, or with a folding machine of any of the 110 usual forms so as to receive and wrap the papers as folded.

While the machine will preferably be used as a high speed machine and suitable devices for feeding both the paper and wrapper and 115 for applying paste to the latter be combined therewith, it is unnecessary to show such devices in the present case, as it is evident that they may be of any suitable construction, it being necessary only to time the feeding devices 120 so that the heads of the paper and wrapper shall reach the feeding roll 40 and disks 41 simultaneously.

With the machine shown, two methods of 125 wrapping differing slightly from each other may be employed. In one, the paper is of a sufficient length to extend about the core one or more times so that the product is delivered from the core in the form of a hollow cylinder which, as above stated, may be finally delivered in that form or reduced to a flat form 130 by a suitable flattening mechanism. This is the method shown in the main views. In wrapping by the second method shown in Fig.

9 the paper extends about half way about the core, so that the wrapper is unsupported on one side when the wrapped paper is delivered from the core, and the spring of the paper 5 causes the latter to spring out to a flat form when released, thus tightening the wrapper upon the product. In this construction the flattening mechanism will generally be found unnecessary, but may be used, if desired, to 10 compress the paper and reduce the thickness of the product. In wrapping by the first method, it is evident that the paper is folded and may be reduced to one-half its original size when the paper extends about the core 15 but once, or a further reduction may be produced by winding the paper upon the core two or more times. In the second construction it is evident that the paper must be reduced to its final length before wrapping, no 20 folding resulting therefrom.

Referring to the drawings, the operation of the mechanism in wrapping by the first method will now be described. The parts being in the position shown in the general views 25 and Fig. 6, the paper *x* and wrapper *y* are fed in simultaneously over the guides 39 by the feeding roll 40 and disks 41 until they are gripped by the core *G* and belts *H*, the tail of the wrapper having been previously provided with paste on the portions between the guides 39, as shown in Fig. 3. They are then advanced together by the core and belts, the latter yielding slightly against the tension of spring 20 according to the thickness of the 30 paper, and upon the second revolution of the core the leading end of the paper and wrapper pass beneath the curved lower ends of the guides 39, which yield against the tension of spring 44. The parts are shown in Fig. 7 just 35 as the leading end of the paper and wrapper are passing guide 52, and about to pass beneath the guides 39. As the leading ends of the paper and wrapper advance from the position shown in Fig. 7, they pass beneath the guides 39, as previously stated, and the wrapper is drawn down over the guides, and as the rear end of the paper passes off the guides, the rear end of the wrapper comes in contact with the first layer of wrapper upon the paper 40 where not separated therefrom by the two inner guides 39, the outside guides 39 being, as previously stated, cut off so as not to extend between the belts and core, and the rear pasted end of the wrapper is gummed down 45 upon the layer of wrapper on the paper to secure the latter by pressure between the belts *H* and the paper on the core, and at the end of the second rotation of the core, it is evident that the paper will be fully wrapped 50 and the rear end of the wrapper secured over a considerable portion of its edges. During the operation thus far described the bowls on levers 36 have been running in the straight part of cam grooves 37, and the cylinders *G* 55 forming the core and the belts *H* have been held in their inner wrapping position, the belts also having been held taut upon the cores but

allowed to yield slightly against the pressure of springs 20 to accommodate the paper, as previously described. As the second rotation 70 of the core is completed and the paper is fully wrapped, however, the bowls on levers 36 are actuated by entering the cam portions of grooves 37, and the levers are moved thereby from the positions shown in full lines in Fig. 75 5 into the positions shown in dotted lines in the same figure, so as to move the frames *E*, *F* corresponding distances outward in opposite directions, thereby withdrawing the cylinders *G* and belts *H* from opposite ends 80 of the wrapped paper, so as to release the latter, and allow it to be delivered between the cylinders. The cylinders and belts are withdrawn during a half of the third rotation of the core, and at the completion of this half 85 rotation and the full release of the paper, the parts are in the position shown in full lines in Fig. 8, and the rear end of the wrapper has passed below the inner guides 39 and is by them pressed upon the body of the wrapped 90 paper so as to secure also the inner pasted portion of the wrapper, and the outer pasted portions of the wrapper have again been pressed by the belts so as to secure the wrapper more firmly. As the frames *E*, *F* are 95 withdrawn, the arms 19 press against the stationary cams 38 and the shafts 18 are thus rocked to raise the pulleys 14, and slacken the belts *H*, so as to allow the belts and cylinders to be readily withdrawn from the paper as indicated in Fig. 8. The paper is now 100 free to fall or be otherwise delivered from between the cylinders, and just at this time the cam 58 on cam disk *K* rocks the shaft 56 through crank arm 57 and against the tension of spring 59 to carry the guide inward from the position shown in full lines in Fig. 8, to that shown in dotted lines in the same figure. The wrapped paper is thus compressed against the inner guides 39 from a circular 105 shape to the oval shape shown in said figure, and is thus carried forward into the control of delivering tapes *L*, and by them advanced, the paper being compressed to its final flat form as it passes between the rolls 62 as 110 shown in dotted lines. The completed product folded and wrapped by this method is 115 shown in perspective in Fig. 10 on the same scale as the general views.

The operation of the construction in wrapping by the second method, as shown in Fig. 9, is substantially the same, and will be understood without further description, it being apparent that the paper is held in the circular curved form only by the belts and core, 120 and that when released therefrom its springs outward so as to strain the wrapper upon the paper, the product being of a width equal to one half the circumference of the core *G*, as in the previous case, but the paper being unfolded. In this construction the guide 52 will 125 operate to throw the unsupported side of the wrapper inward toward the body of the paper, thus assisting in the process of delivery.

The product of the second method is shown in perspective in Fig. 11, on the same scale as the general views.

In the drawings it is evident that the paper is wound about the core but once or more, but it is evident that this will depend upon the length of the paper, and the size of the core employed. In the construction shown the core is designed to be about seven inches in circumference, so that the papers wrapped by the first method are previously folded to a length of about seven inches, and the product is about three and a half inches wide. These relative sizes of core and paper will be found to produce a product of convenient form, as shown in Figs. 10 and 11. It is evident, however, that with a core of this size papers of any desired length may be wrapped by increasing the number of rotations of the core before delivery, and lengthening the wrapper the construction being modified in an obvious manner for this purpose. While this size of core will be found convenient, it is evident that if a smaller and more closely wrapped product be desired, the size of the core may be reduced to any extent desired, and that on the other hand the size of the core may be increased so as to form products of larger size, this depending upon the size, thickness, and character of the publications to be wrapped.

As above stated, the flattening mechanism may be omitted and the papers be delivered in the circular form by the first method, or in flat form by the second method. With light newspapers and a core of considerable size, this construction would not be desirable with the first method, but with a smaller core on which the paper is rolled tightly, such a construction is practical, and with thick magazines and similar publications the circular may be found the preferred form of product.

What I claim is—

1. The combination with a core, of feeding devices co-acting therewith to advance a paper and wrapper and wind them upon the core by pressure between the feeding devices and core, and means for delivering the wrapped paper from the core, substantially as described.

2. The combination with a rotating core, of feeding devices co-acting therewith to advance a paper and wrapper and wind them upon the core by pressure between the feeding devices and core, and means for delivering the wrapped paper from the core, substantially as described.

3. The combination with a core, of belts moving about said core and co-acting therewith to advance a paper and wrapper and wind them upon the core by pressure between the belts and core, and means for delivering the wrapped paper from the core, substantially as described.

4. The combination with a rotating core, of belts moving with said core and co-acting

therewith to advance a paper and wrapper and wind them upon the core by pressure between the belts and core, and means for delivering the wrapped paper from the core, substantially as described.

5. The combination with a core, of spring pressed belts moving about said core and co-acting therewith to advance a paper and wrapper and wind them upon the core by pressure between the belts and core, and means for delivering the wrapped paper from the core, substantially as described.

6. The combination with a core, of belts moving about said core and co-acting therewith to advance a paper and wrapper and wind them upon the core by pressure between the belts and core, means for delivering the wrapped paper from the core, and means for slackening said belts for the delivery of the wrapped paper, substantially as described.

7. The combination with a core mounted to move longitudinally, of feeding devices co-acting therewith to advance a paper and wrapper and wind them upon the core by pressure between the feeding devices and core, and means for withdrawing the core from the wrapped paper to deliver the paper, substantially as described.

8. The combination with a core, of feeding devices co-acting therewith to advance a paper and wrapper and wind them upon the core by pressure between the feeding devices and core, said core and feeding devices being mounted to move longitudinally of the wrapped paper, and means for withdrawing the core and feeding devices to deliver the wrapped paper from the core, substantially as described.

9. The combination with a rotating core, of belts moving with said core and co-acting therewith to advance a paper and wrapper and wind them upon the core by pressure between the belts and core, said core and belts being mounted to move longitudinally of the wrapped paper, and means for withdrawing the core and belts to deliver the wrapped paper from the core, substantially as described.

10. The combination with a core consisting of two cylinders adapted to support a paper at opposite sides and mounted to move longitudinally, of feeding devices co-acting therewith to advance a paper and wrapper and wind them upon the core by pressure between the feeding devices and core, and means for withdrawing said cylinders from the wrapped paper in opposite directions to deliver the paper, substantially as described.

11. The combination with a core consisting of two cylinders adapted to support a paper at opposite sides and mounted to move longitudinally, of feeding devices co-acting therewith to advance a paper and wrapper and wind them upon the core by pressure between the feeding devices and core, means for withdrawing said cylinders from the wrapped paper in opposite directions to deliver the pa-

per, and a flattening mechanism to which the wrapped paper is delivered from the wrapping mechanism, substantially as described.

12. The combination with a core consisting of two cylinders adapted to support a paper at opposite sides, of feeding devices co-acting therewith to advance a paper and wrapper and wind them upon the core by pressure between the feeding devices and core, said core and feeding devices being mounted to move longitudinally of the wrapped paper, and means for withdrawing said cylinders and feeding devices from the wrapped paper in opposite directions to deliver the paper, substantially as described.

13. The combination with a core consisting of two cylinders adapted to support a paper at opposite sides, of belts moving about said core and co-acting therewith to advance a paper and wrapper and wind them upon the core by pressure between the feeding devices and core, said core and belts being mounted to move longitudinally of the wrapped paper, and means for withdrawing the cylinders and belts from the wrapped paper in opposite directions to deliver the paper, substantially as described.

14. The combination with a core, consisting of two cylinders adapted to support a paper at opposite sides of belts moving about said core and co-acting therewith to advance a paper and wrapper and wind them upon the core by pressure between the feeding devices and core, said core and belts being mounted to move longitudinally of the wrapped paper, means for withdrawing the cylinders and belts from the wrapped paper in opposite directions to deliver the paper, and means for slackening the belts during the withdrawal, substantially as described.

15. The combination with a core consisting of two rotating cylinders adapted to support a paper at opposite sides, of feeding devices co-acting therewith to advance a paper and wrapper and wind them upon the core by pressure between the feeding devices and core, said core and feeding devices being mounted to move longitudinally of the wrapped paper, and means for withdrawing said cylinders and feeding devices from the wrapped paper in opposite directions to deliver the paper, substantially as described.

16. The combination with a core consisting of two rotating cylinders adapted to support a paper at opposite sides, of spring pressed belts moving with said cylinders and co-acting therewith to advance a paper and wrapper and wind them upon the core by pressure between the feeding devices and core, said cylinders and belts being mounted to move longitudinally of the wrapped paper, means for withdrawing said cylinders and belts from the wrapped paper in opposite directions to deliver the paper, and means for slackening the belts during withdrawal, substantially as described.

17. The combination with the rotating cyl-

inders G, of feeding devices co-acting with said cylinders to wind a paper and wrapper thereon, and guides 39 over which the paper and wrapper are fed to the cylinders, and beneath which they pass on the second rotation of the cylinders, substantially as described.

18. The combination with the cylinders G, of feeding devices co-acting with said cylinders to wind a paper and wrapper thereon, means for withdrawing the cylinders in opposite directions to release the wrapped paper, and a guide 52 reciprocating between the cylinders to deliver the paper, substantially as described.

19. The combination with the cylinders G, of feeding devices co-acting with said cylinders to wind a paper and wrapper thereon, means for withdrawing the cylinders in opposite directions to release the wrapped paper, a flattening mechanism, and a guide 52 reciprocating between the cylinders to deliver the paper to the flattening mechanism, substantially as described.

20. The combination with cylinder G, of a belt H co-acting with said cylinder to wind a paper and wrapper thereon, mechanism for driving said cylinder and belt, a cam and connections for withdrawing the cylinder and belt from the wrapped paper and returning them to position to receive another paper, and means for holding the paper during the withdrawal of the cylinder and belt substantially as described.

21. The combination with the sliding frames E, F, of cylinders G and belts H carried thereby, mechanism for driving said cylinders and belts, and means for withdrawing said cylinders and belts in opposite directions and returning them to position, substantially as described.

22. The combination with the sliding frames E, F, of cylinders G and belts H carried thereby, shaft D and connections for driving said cylinders and belts, cams I carried by said shaft, and levers 36 actuated by said cams and connected to said frames, substantially as described.

23. The combination with the cylinder G, of belt H coacting with said cylinder to wind a paper and wrapper thereon, a spring pressed rock arm on which one of the belt pulleys is mounted, whereby the belt is held against the cylinder under spring tension, means for withdrawing the core and belt from the wrapped paper, means for holding the wrapped paper during such withdrawal and a cam and connections for rocking said arm against the spring pressure to slacken the belt, substantially as described.

24. The combination with paper wrapping mechanism advancing the paper and wrapper in a circular path to wind or roll the paper and wrapper together, and constructed to release the wrapped paper for sidewise delivery, of an ejector moving transversely to the paper, substantially as described.

25. The combination with paper wrapping

- mechanism advancing the paper and wrapper in a circular path to wind or roll the paper and wrapper together, and constructed to release the wrapped paper for sidewise delivery, of
5. a member forming a guide for the paper during the wrapping operation, and means for moving said guide transversely to the wrapped paper to deliver the latter, substantially as described.
10. 26. The combination with paper wrapping mechanism engaging the paper at opposite sides and constructed to release the wrapped

paper, of a member forming a guide for the paper during the wrapping operation, and means for reciprocating said guide transversely to the wrapped paper to deliver the latter, substantially as described. 15

In testimony whereof I have hereunto set my hand in the presence of two subscribing witnesses.

LUTHER C. CROWELL.

Witnesses:

L. E. HOWARD,
J. J. KENNEDY.
